TABLE TOP CIRCULATOR

Ottis A. Sutton, Wichita, Kans., assignor to The
O. A. Sutton Corporation, Inc., Wichita, Kans.,
a corporation of Kansas

Application March 24, 1950, Serial No. 151,721

7 Claims. (Cl. 230—259)

1

My present invention comprises an air circulator including an adjustable fan unit pivotally mounted upon a horizontal axis in such fashion as to remain in any of a plurality of positions to which it may be moved, in one position directing air upwardly and in other positions directing a stream of air laterally at any desired angle to the horizontal, the air circulator comprising a supporting stand including a deflector cone mounted above the fan unit in coaxial relation thereto when vertically positioned so as to spread the air angularly in all directions. The unit may be moved about the room to any desirable or convenient position and may create either a gentle circulation by directing air upwardly and laterally in all directions while drawing air from the room in all directions, or may be positioned to direct a concentrated, whirling beam of air horizontally or at an angle across a room, thus providing means for achieving complete circulation without drafts, or spot cooling without drafts.

A further object of the present invention is to provide an air circulator of the foregoing type which also may serve as an end table, coffee table, plant stand or the like, the unit being so constructed as to provide a supporting surface upon which articles may be placed without in any way interfering with the operation of the fan unit.

A further object of the present invention is to provide an air circulator of the foregoing character which is provided with simple but effective means for preventing the rotation of the fan unit about its horizontal axis more than a limited amount in either direction, thus preventing damage to the unit.

The foregoing and other objects and advantages of the present invention may be more readily ascertained by inspection of the following specification taken in connection with the accompanying drawing wherein like numerals refer to like parts throughout, while the features of novelty will be more distinctly pointed out in the appended claims.

In the drawing,

Fig. 1 is a view in elevation of the air circulator unit showing the fan positioned to direct a stream of air vertically upward;

Fig. 2 is a view in elevation, with parts broken away, of the unit rotated a few degrees clockwise from the position of Fig. 1 and showing the fan positioned to direct a stream of air at an inclination to the horizontal;

Fig. 3 is a view in elevation, with parts broken away, of the unit rotated ninety degrees clockwise from the position of Fig. 2 and showing the fan in a horizontal position;

Fig. 4 is a partial, vertical section, on an enlarged scale, taken substantially along line 4—4 of Fig. 2;

2

Fig. 5 is a partial, horizontal section taken from the plane of line 5—5 of Fig. 2; and

Fig. 6 is a partial, vertical section taken substantially from the plane of line 6—6 of Fig. 5.

The air circulator unit of the present invention comprises a table top 10 to which is affixed a deflector cone 11 and three legs 12, 13 and 14, the legs being substantially identical but being separately numbered so as to facilitate correlation of the views with each other. The table top 10 preferably comprises a formed, disclike member having a raised edge portion 15 to prevent articles from sliding off of the edge thereof, and a downwardly turned flange 16 including an ornamental bead flange 16. The deflector cone 11 is a formed disclike member having its edge received in the groove provided by the bead flange 16, the two parts being assembled by rolling the edge of the top 10 over the edge of the cone 11. The cone is therefore maintained in concentric relation to the round table top with its edge extending to the edge of the table top and its apex directed downwardly at the center of the construction. For ease of manufacture the cone is slightly truncated, but such configuration is not critical.

There could be a different number of legs, but three are sufficient for stability, provide an attractive appearance, and also provide a wide space through which the air stream may be directed without interference when the fan is tipped angularly or horizontally outward. Each leg comprises a channel-shaped member having its web 20 outward and its flanges 21 directed inward so as to provide a hollow space opening toward the vertical centerline of the unit. The legs are formed and are then assembled with end pieces which hold the legs in formed shape, the end pieces comprising an upper end piece 22 and a lower end piece 23. The upper end piece comprises a strap substantially in the form of a handle, with the bight portion thereof of spanning the upper edges of the flanges 21, the vertical portions thereof being spot-welded to the flanges 21 as indicated at 24, and the laterally directed tips 25 thereof projecting outwardly through notches 26 in the upper edges of the flanges 21. The deflector cone 11 is preferably provided with screw-receiving apertures while being formed for the reception of sheet metal screws 27 passing through apertures in the tips 25 so as to hold the legs to the table top at equiangular spacing about the vertical centerline of the unit. The lower end pieces 23 each comprise a horizontal portion in which a depression 28 may be formed to provide a supporting foot and three upwardly turned tabs 29 which are welded to the flanges and web of the leg.

A fan-supporting ring 30 is supported by the legs in a horizontal position at an intermediate level, the ring being formed from half-inch

round bar stock or equivalent. In order to support the ring each of the flanges 21 is notched as indicated at 31 to receive substantially half the diameter of the ring, and in order to prevent spreading of the lower ends of the legs the flanges 21 are welded to the ring on their inner surfaces as indicated at 32. Preferably the joint 33 holding the ends of the ring together is located midway between the flanges 21 of one of the legs, thus eliminating the necessity for making a smoothly finished ground joint. The ring may be made of two or more sections for convenience, in which case all of the joints may be located as shown in Fig. 6.

The ring is provided with two flattened areas 35 at diametrically opposed points, lying along a diameter normal to a plane passing through the vertical centerline of the unit and the center of one of the legs, in this case leg 12. A fan unit is pivotally mounted for rotation about the horizontal diameter thus defined, by pivot means such as disclosed in my copending application, Serial No. 120,502, filed October 10, 1949, now Patent No. 2,554,600 dated May 29, 1951, the fan unit being preferably such as disclosed in my copending applications, Serial Nos. 120,503 and 120,504, both filed October 10, 1949 now Patents Nos. 2,554,601 and 2,554,602 respectively, both dated May 29, 1951. The fan unit therefore comprises a hollow, air directing cowl 40 in which is mounted an air directing inlet funnel 41 and a motor 42, the three portions being concentrically located with respect to each other, and the motor being attached to and driving a fan indicated at 44 rotating within the cowl 40 ahead of the forward edge of the funnel 41 so as to project a circulating, beamed stream of air through the forward end of the cowl. The fan therefore rotates about an axis midway of the pivots and at right angles to the diameter along which the pivots lie. The forward end of the cowl is preferably spanned by a grille 45 preventing accidental contact with the fan blades. A conical, inwardly tapering pivot member 46 is mounted upon the cowl by a bolt 47 and nut 48, the member 46 complementarily fitting into an inwardly tapering opening through the flattened portion 35 of the supporting ring. The ring is so formed as to be initially outwardly stressed at the portions 35 and the bolts 47 may be tightened so as to stress the ring inwardly when the fan is positioned upon the structure, for this purpose the nuts 48 being welded to the inner surface of the cowl prior to the assembly of the cowl's component parts. The tapering member 46 is preferably formed of brass having a high coefficient of friction with respect to the iron of which the ring is made so that the frictional resistance to rotation of the fan unit about its horizontal axis is sufficient to overcome any tendency of vibration of the unit to displace the unit from a selected position. However, the fan unit is substantially balanced about its pivotal axis so that when positioned at any position it will not have much tendency to swing to any other position. The construction is such that positioning of the fan unit at any desired angularity may be readily accomplished by pushing or pulling upon some portion of the cowl or of the funnel, and may be accomplished while the fan is in operation.

The electric motor 42 may be connected to a source of current through a cable 50 preferably having a plug-in connector (not shown)

at its free end, the cable being led into the lower end of the leg 12 through a grommet 51 closely adjacent the foot of the leg so that the cable may be concealed beneath floor rugs or the like. The cable 50 runs up within the leg 12 to control means mounted in the enlarged, hollow upper end of the leg, such means being exemplified by a switch box 52 from which projects a control knob 53 conveniently located at an upper level so as to be readily accessible. From the control means a motor cable 54 is led downwardly through the hollow leg, behind and underneath the ring 30, and then outwardly to the motor. The cable 54 is made of such length that the fan unit may be swung about its horizontal axis from the vertical position shown in Fig. 1 to the horizontal position shown in Fig. 3, and beyond that position to a slight downward inclination at which point the cable 54 becomes tightened and prevents further rotation so that the fan unit is prevented from rotating through a complete revolution in that direction. When the fan unit is swung in the opposite direction the edge of the funnel 41 engages the cable 54 when the unit is swung a few degrees beyond the vertical, thus preventing horizontal positioning of the fan unit in such manner as to direct an air stream against the leg 12. The fan unit therefore can be directed horizontally only through the clear space between legs 13 and 14. The limits of rotation of the fan unit serve another purpose in that motor 42 is restricted in its movement from a vertical position to a substantially horizontal position in one direction only, whereby the motor is always maintained in proper operating positions. Thus the oil inlets and ducts are always uppermost or so positioned as to permit the flow of oil to the bearings and prevent dripping of oil onto carpets or the like.

The upper portion of each leg supports a member 60 spanning the inner edges of the flanges 21, the member 60 being attached to the legs by integral flanges 62 drilled to receive the tips of sheet metal screws 63. The lower ends of the members 60 extend downwardly between the edges of the flanges, being bent rearwardly to conform to the curved edges thereof shaped to clear the cowl in its swinging movement, and being supported in such position by extensions 64 on the flanges 62 which are bent inwardly at an angle and welded to the downwardly projecting portion of the member 60. The hollow spaces between the flanges of the legs are thus substantially closed to enhance the ornamental appearance of the unit and to protect the control members within the leg 12.

The members 60 provide supporting surfaces upon which a pair of guard rings 65 are mounted, the rings being concentrically located beneath the deflector cone. The rings are supported by a bracket member 66 provided with oppositely disposed, hooked arms which partially surround the ring, the central portions of the brackets being mounted upon the members 60 by bolts 67 and nuts 68. The rings 65 not only provide an ornamental effect but safeguard against injury by making it difficult for a person to reach into the top of the fan unit when positioning the fan, causing him to reach underneath the fan unit to engage the funnel 41, or to press upon the outer surface of the cowl 40 rather than to position his fingers within the cowl.

Having illustrated and described a preferred embodiment of my invention, it should be ap-

parent to those skilled in the art that the invention permits of modification in arrangement and detail. I claim as my invention all such modifications as come within the true spirit and scope of the appended claims.

I claim:

1. An air circulating unit comprising a plurality of equiangularly spaced legs, a round table top supported by said legs, a conical deflector concentrically underlying said table top and having its edge extending to the edge of said table top and its apex downward, a supporting ring affixed to said legs at an intermediate level concentrically with respect to said table top, a diametrically opposed, inwardly directed pair of pivots mounted on said supporting ring on a line normal to a plane bisecting the angle between two of said legs, and a fan unit pivotally supported on said pivots and including a fan rotatable about an axis midway between the pivots and at right angles to the diameter along which the pivots lie, said fan unit being movable about said pivots to direct a stream of air upward against said deflector or to direct a stream of air laterally between said two legs.

2. An air circulating unit comprising three equiangularly spaced legs, a table top supported by said legs, a conical deflector underlying said table top and having its edge concentrically arranged with respect to said table top and its apex downward, a supporting ring affixed to said legs at an intermediate level concentrically with respect to said table top, a diametrically opposed pair of pivots mounted on said supporting ring on a line normal to a plane bisecting the angle between two of said legs, and a fan unit pivotally supported on said pivots and including a fan rotatable about an axis midway between the pivots and at right angles to the diameter along which the pivots lie, said fan unit being movable about said pivots to direct a stream of air upward against said deflector or to direct an unimpeded stream of air laterally between said two legs.

3. An air circulating unit comprising three equiangularly spaced legs, a table top supported by said legs, a conical deflector underlying said table top and having its edge concentrically arranged with respect to said table top and its apex downward, a supporting ring affixed to said legs at an intermediate level concentrically with respect to said table top, a diametrically opposed pair of pivots mounted on said supporting ring on a line normal to a plane bisecting the angle between two of said legs, and a fan unit pivotally supported on said pivots and including a fan rotatable about an axis midway between the pivots and at right angles to the diameter along which the pivots lie, said fan unit being movable about said pivots to direct a stream of air upward against said deflector or to direct an unimpeded stream of air laterally between said two legs, said pivots comprising means frictionally resisting movement of said fan unit.

4. An air circulating unit comprising a table including three equiangularly spaced legs, the lower surface of the top of said table comprising a downwardly directed, conical deflector, a supporting ring mounted upon said legs in a horizontal position at an intermediate level, a pair of diametrically opposed pivots mounted on said supporting ring on a line normal to a plane bisecting the angle between two of said legs, a fan unit pivotally supported by said pivots concentrically within said legs and movable from a vertical position to a laterally directed position, said fan unit

comprising an electric motor and a propeller fan driven by said electric motor to rotate about an axis midway between said pivots and at right angles to the diameter along which said pivots lie, and a current supply cable connecting said electric motor to a fixed portion of said table, said current supply cable being of such length as to limit rotation of said fan unit in either direction about said pivot means.

5. An air circulating unit comprising three equiangularly spaced hollow legs, a table top supported by said legs, a horizontally disposed ring mounted on said legs at an intermediate level, a pair of diametrically opposed pivots mounted on said ring on a line normal to a plane bisecting the angle between two of said legs, a fan unit pivotally supported by said pivots, said fan unit comprising an electric motor, a propeller fan driven by said electric motor to rotate about an axis midway between said pivots and at right angles to the diameter along which said pivots lie and concentrically arranged air directing means surrounding said motor and fan, control means for said motor mounted within one of said hollow legs, and a current supply cable connecting said control means and said motor, said current supply cable being of such length as to limit rotation of said fan unit in either direction about its horizontal axis.

6. An air circulator comprising three equiangularly spaced legs, a table top supported by said legs, a conical deflector underlying said table top and having its edge concentrically arranged with respect to said table top and its apex downward, a supporting ring affixed to said legs at an intermediate level, a diametrically opposed pair of pivots mounted on said supporting ring on a line normal to a plane bisecting the angle between two of said legs, and a fan unit pivotally supported on said pivots whereby said fan unit may be positioned vertically to direct a stream of air upward against said deflector or may be positioned to direct an unimpeded stream of air laterally between said two legs, and a plurality of guard rings concentrically mounted upon the upper portions of said legs.

7. An air circulator comprising a plurality of legs, a round table top supported by said legs, a supporting ring affixed to said legs at an intermediate level concentrically with respect to said table top, a diametrically opposed pair of pivots mounted on said supporting ring on a line normal to a plane bisecting the angle between two of said legs, and a fan unit pivotally supported on said pivots and including a fan rotatable about an axis midway between the pivots and at right angles to the diameter along which the pivots lie, said fan unit being movable about said pivots to direct a stream of air upward against said table top or to direct an unimpeded stream of air laterally between said two legs.
